UNITED STATES PATENT OFFICE.

ROBERT A. BROOKS, OF CHICAGO, ILLINOIS.

FLUID-CONTROLLED FLUSHING-VALVE.

No. 882,740.

Specification of Letters Patent. Patented March 24, 1908.

Application filed June 4, 1906. Serial No. 320,081.

To all whom it may concern:

Be it known that I, ROBERT A. BROOKS, a citizen of the United States, and a resident of the city of Chicago, in the county of Cook and State of Illinois, have invented certain new and useful Improvements in Fluid-Controlled Flushing-Valves; and I do hereby declare that the following is a full, clear, and exact description of the same, reference being had to the accompanying drawings, and to the letters of reference marked thereon, which form a part of this specification.

This invention relates to improvements in flushing valves and more particularly to that class of flushing valves set forth in my prior application for patent for improvements in flushing valves, filed October 26, 1905; Serial No. 284,543.

In the older types of flushing valves the adjustment to operate at water pressure below four or five pounds was difficult or impossible hence such valves did not go into general use. Most of the flushing valves in use would work fairly well with high or medium pressures were it not that most valves for this purpose contain tortuous channels and passages usually of very small size and therefore likely to become clogged or stopped up by the deposit of sediment contained in the water, in consequence the efficiency of such are very uncertain.

The object of this invention is to afford a valve of the class described wherein the full opening of the valve is insured independent of the water pressure exerted against the same and in which the closure is positive after a regulated flush and after fill.

It is also an object of the invention to construct the valve of few parts and to enable the parts when adjusted to be rigidly held from unauthorized interference.

It is also an important object to construct the valve with large ports, perfectly controlled and in which clogging is impossible.

Lastly it is an object of the invention to regulate the period of the duration of the flush by means of a fluid other than that passing through the valve and to so inclose and contain said fluid as to prevent the loss by leakage or otherwise therefrom in whatever position the valve may be placed.

The invention consists in the matters hereinafter described and more fully pointed out and defined in the appended claims.

In the drawings: Figure 1 is a central vertical section of a device embodying my invention showing the valves fully closed. Fig. 2 is a similar view showing the valves fully opened and with parts shown in elevation. Fig. 3 is a top plan view of the valve. Fig. 4 is a section taken on line 4—4 of Fig. 1. Fig. 5 is a section taken on line 5—5 of Fig. 4. Fig. 6 is a reduced bottom plan view of the piston. Fig. 7 is a section taken on line 7—7 of Fig. 1 with parts removed.

As shown in the drawings: A indicates a casing which as shown is cylindric and constructed of cast metal or other suitable material and in the bottom of which is connected as shown, a vertical inlet pipe a and from the side of said casing above the center thereof opens a laterally directed outlet pipe a' leading to the fixture to be flushed. Below said outlet pipe is provided an inwardly projecting horizontal peripheral flange a², which affords an upwardly facing shoulder and supported thereon is a downwardly facing valve seat B, between which and said shoulder is provided a packing washer b. Said seat as shown projects downwardly on the inner side of the flange a² and is provided at a slight distance from the inner periphery with a downwardly opening groove concentric therewith as indicated by b². Threaded in an upwardly projecting concentric flange on the upper face of said seat is a cylindric sleeve B' and fitted around the upper end of the same and bearing on the upper externally threaded end of said casing is a packing washer b'. A flanged cap A' is threaded on the upper end of the casing A and compresses said packing washer b' on said upper end of the casing and also by pressure on said sleeve B' forces said seat B downwardly on the shoulder or flange a² affording tight joints. Said sleeve as shown at the lower end of the same is provided with relatively large horizontally extended apertures through which the water in flushing is delivered into the portion of the casing above said shoulder or flange a², which divides said casing into an upper and a lower chamber. Said cap A' is provided with an upwardly directed internally threaded flange a³, concentric therewith and in which is threaded a cylindric shell or housing C which at its upper end is closed by means of a cap C'. Vertically slid-

able within said shell or housing is a cylindric fluid containing cup D which as shown is provided with a closed bottom d and at its top is provided with a cap d' which is threaded thereon, and which as shown presses a suitable packing washer d^2 , upon the upper edge of the cup and thereby seals a joint. Said cap d' is provided with a central stuffing box or gland therethrough, through which extends a tubular stem, E which is internally threaded and the extremities of which are externally threaded. The upper end of said stem E is threaded through a nut e , which is loosely seated in a central aperture in the cap C' , and threaded on the upper end of said stem and serving as a jam nut for the nut e is a cap nut e' which also closes the end of the stem. Fitted for said cup to slide relatively of the same within the cup D and secured on the lower end of said stem E which is threaded therethrough is a piston E' . Said piston is provided with a recess therein, open at its bottom and opening therethrough at its top in a restricted port or aperture and secured within the recess is a ball F, which serves as a closure for said port to prevent the oil or liquid with which the cup is filled, from flowing upwardly therethrough. Said tubular stem E at a point slightly above the piston is provided with apertures or ports therethrough and threaded within the stem and extending downwardly to partly close said parts if desired is a threaded rod e^3 , which when threaded inwardly serves to restrict said ports opening through the stem and when threaded upwardly therein opens the same. The upper end of said rod as shown is notched for engagement with a screw driver or other suitable tool for adjustment. A coiled spring E^2 is engaged around said stem and bears upon the piston and against the cap or cover d' for the cup and serves normally to hold the cup elevated. The cover d' of the cup is provided at one side of the center of the same with an upwardly projecting externally threaded boss G and threaded thereon is the operating stem or rod G' , which projects through a suitable aperture in the cap C' and is provided at its upper end with a push button g or other suitable actuating means. Threaded on the stem E, is an arm g'' which fits closely beneath the cover C' and jams the nut e at the lower side of the same and is forked at its outer end and engages partly around the operating stem G' and acts to hold said stem and piston from rotation.

Threaded centrally in the lower end of the cup D is an axial downwardly extending rod 60 or stem H which passes through a suitable gland h , in the cap A' of the casing. The lower end of said stem normally projects into the upper end of the inlet pipe. Slidable in the sleeve B' , and in the chamber below the 65 valve seat is the differential valve of which

the upper and larger portion comprises a piston I, fitting loosely in said sleeve B' and is provided with a central enlarged passage extending therethrough and through its vertically ribbed or grooved stem i , to afford a 70 water passage and through which the stem H extends. At the lower end of said stem i of the differential valve is a circular downwardly facing head I' provided with a peripheral upwardly directed flange I^2 which fits 75 in the aperture through said seat and as shown is provided with a peripherally elongated but narrow aperture therethrough at one or more points and near its bottom. Below said flange said stem is externally 80 threaded and the passage therethrough is enlarged to afford a chamber and threaded on said lower end of said stem is a peripherally flanged nut i^3 which bears a packing washer i^4 upwardly against said downwardly facing head I' and which closes against said seat B, when the valve is closed. Said nut i^3 at its bottom is restricted or partly closed. Through the aperture therethrough extends a ribbed spider h' , carried on the lower 90 end of the stem H, and above which is provided a notched plate or collar h^2 which is adapted to bear against the inner face of said nut and force the valve downwardly to its open position. At the lower end of said 95 stem and bearing against said spider h' , is a vent valve comprising a packing washer h^3 which closes against the end of said nut and is held in place by a jam nut h^4 , secured on the lower end of said stem H. 100

The operation is as follows: The spring E^2 normally holds said cup elevated with the fluid therein above the piston E' and inasmuch as the stem H is rigidly connected with the bottom of the cup the valve is obviously 105 held closed thereby. When it is desired to open the valve the cup is forced downwardly by means of the stem G' , whereby the liquid in said cup flows quickly through the piston downwardly and causes the ball F to fall to the bottom or larger portion of the recess in 110 said piston affording a free vent through the piston and permitting the cup to move downward with but little resistance. The downward movement of the cup obviously forces the vent valve h^3 open permitting the flushing fluid to flow upwardly through the differential valve under inlet pressure and to fill the chamber above the piston I. This being larger than the inlet valve I' the valves 115 are forced downwardly affording a quick opening and the water from the inlet flows through said seat into the sleeve B' . It is desirable that the passage through the differential valve and the stem connecting the 120 parts thereof should be relatively large. Should the water pressure be very slight as in some situations occurs gravity aids the pressure in opening the valve and in any event should there be any tendency for the 125 130

valve to stick the notched collar h^2 , on the stem H, engages within the nut i^3 and the valve is forced open manually.

The valve being open it is desirable in regulating the flush to restrict the return flow of the fluid above the piston due to the upward movement of the cup carrying the valves therewith. It is obvious that the ball F, under such upward pressure seats to close the port through said piston so that the flow is limited entirely to that passing through the stem and possibly a slight leakage around the piston. The amount passing through the stem is controlled by the inward or outward adjustment of the rod e^3 thereby varying the delivery through the ports in said stem above the piston and in this way enabling the return flow to be regulated for a long or a short period as desired.

Obviously none of the fluid or oil within the cup D can be spilled in transportation or otherwise as it is inclosed within the cup by its cover and obviously in consequence evaporation cannot cause the same to become thickened through use. It follows that the valve when once assembled and adjusted is capable of working indefinitely without further attention.

It is evident that the valve must open and close entirely independent of the pressure exerted at the inlet as the opening of the same is insured. First, by the differential action of the inlet pressure upon the piston I and the inlet valve I'. Second, by gravity as the valve of necessity opens downward and third by the positive downward movement of the stem therethrough which forces the valve open should the same not have opened as the stem nears its downward limit of movement. It is also evident that the valve in closing can never hammer for the reason that the preliminary upward movement of the oil cup serves to close the vent valve h^2 and the continued upward movement of said cup and stem carries the valve upwardly slowly permitting the water above the piston I, the larger head of said differential valve, to escape to the outlet around said piston. As the valve I' approaches its seat the flange I² cuts off the major part of the flow and there is just sufficient passing through the slot or aperture in said flange to afford the afterfill and this is of course cut off when the valve seats. The continued upward pressure exerted thereon by the stem H and the tendency of the upwardly flowing water to the same is resisted still to a certain extent by the water above the piston I and should there be any tendency whatever for said valve to lift suddenly from the vent valve, the pressure is instantly restored above the piston thus preventing hammering.

Obviously while I have described a certain mechanical construction for the valves and the connections between the same it is

evident that various detail changes may be made without varying from the principles of this invention.

I claim as my invention:

1. A valve of the class described embracing a casing having an inlet and an outlet pipe, a valve seat in the casing, a differential closure for said seat, a vent valve in said closure adapted to be manually actuated preliminary to flushing, adapting inlet pressure and gravity to unseat the closure, a closed fluid containing cup regulating the closure and means rigidly engaged to said cup and extending through the top of the casing for manual actuation.

2. A valve of the class described embracing a casing having an inlet and an outlet pipe, a seat in the casing, a differential closure for said seat, a valve controlled passage in the closure adapted to admit inlet pressure above the same, said closure adapted to be opened by manual actuation and aided by gravity, inlet pressure and manually and a closed movable fluid containing cup regulating the closure.

3. A valve of the class described embracing a casing having an inlet and an outlet, a valve seat in the casing, a differential closure normally seated on said seat adapted to be unseated by inlet pressure, gravity and manually prior to flushing, a closed movable cup containing a fluid and means through which the fluid passes to vary the rate of closing of said differential closure.

4. A flushing valve of the class described embracing a casing having an upwardly opening inlet and laterally opening outlet pipe, an inlet valve closing with the pressure to close the inlet pipe, a vent valve controlling the same, a wholly closed fluid containing vessel, a piston therein, one of the same movable relative to the other, a stem connecting said movable element to open the vent valve and means for actuating said movable element.

5. A flushing valve of the class described comprising a casing having an inlet and an outlet, a valve seat in the casing, a closure therefor, manually operated means adapted when actuated to open the closure by manual actuation, gravity and inlet pressure a wholly inclosed cup within the casing having a fluid therein, a free stem projecting thereinto, a piston rigidly secured to the lower end of the stem and means locking said stem and piston from rotation.

6. A flushing valve of the class described embracing a casing, an inlet pipe opening upwardly into the bottom thereof, an outlet pipe opening laterally therefrom, a valved partition dividing the casing below the outlet, an inlet valve seated in said partition and opening downwardly into the inlet pipe, a vent valve carried on said inlet valve and also opening downwardly, a piston rigidly connected with the inlet valve and of greater

- area and exposed to inlet pressure from above, downwardly when the vent valve is opened, a closed fluid containing cup above the valves, a piston therein, means for moving one relatively of the other, a stem connecting the movable element with the vent valve closure and one or more valves controlling the flow through said piston in the cup.
- 10 7. In a valve of the class described the combination with a casing having an inlet and an outlet of a closure adapted to afford and cut off communication between the same, a tightly closed movable cup in the 15 casing containing a fluid, a stuffing box movable with the cup, a stem extending therethrough, means rigidly engaged to the cup for actuating the same, means secured to the stem in the cup dividing the cup into chambers and adapted to control the rate of flow 20 of fluid, from one chamber to the other and operative connections between the cup and closure whereby the movement of the closure is regulated by the movement of the cup.
- 25 8. In a flushing valve of the class described a casing having an inlet and an outlet, a valve seat therein, a downwardly opening differential valve for said seat, mechanism operatively connected with the closure adapted 30 when operated to open said differential valve manually aided by inlet pressure and gravity, a wholly closed cup containing a fluid, a rigid valved piston therein and operative connections whereby the closure of said 35 valve is controlled by the relative movement of said cup and the piston.
9. In a device of the class described the combination with a valve of a closed fluid containing cup, a tubular stem extending 40 into the cup having an aperture through the side thereof, a valved piston secured to the stem in the cup, a rod threaded into said stem adapted for adjustment to vary the amount of fluid admitted through the aperture in the stem, means integral with the cup 45 adapted for connection with an actuation handle or stem, a lock adapted to prevent said piston from rotation and operative connections between the cup and valve.
- 50 10. In a device of the class described a movable wholly closed, regulating cup, a fluid filling the same, a rigidly fixed piston therein having a regulable port therethrough, a valve in the piston closing against upward 55 pressure, means for regulating said port and a lock holding said piston from rotation.
11. In a device of the class described regulating means embracing a wholly closed vertically movable regulating cup, a stuffing box 60 in the top thereof, a tubular stem extending therethrough and into the cup, a head, a stem fitting in the cup, an adjustable rod threaded in the stem and regulating ports through the piston, means loosely supporting said stem 65 and holding the same from rotation and man-
- ually operated means rigidly engaged to the cup.
12. In a flushometer the combination with a casing of an inlet and an outlet pipe therefor, a valve seat in said casing, a differential valve closure adapted to close the inlet, means admitting inlet pressure on the larger area of the closure to unseat the same by and against inlet pressure, a spider adapted by 70 said means to aid in opening said closure and means rigidly engaged to the closure to provide an after fill.
13. In a flushometer the combination with a casing of an inlet and an outlet pipe therefor, a valve seat in said casing between said pipe, a differential valve closure adapted to seat thereon, means admitting inlet pressure to unseat the closure, manually actuated means adapted to engage the closure to aid 75 inlet pressure in unseating the same a wholly closed fluid containing cup, a piston in said cup through which the fluid in the cup flows, means locking the cup and piston from rotation and an apertured flange movable with 80 said closure adapted to extend on opposite sides of the valve seat to provide an after fill.
14. In a flushometer the combination with a casing having an inlet and an outlet pipe, a removable valve seat in said casing, a removable sleeve holding the seat in place and 85 having a plurality of apertures therein, a closure adapted to seat on said seat and having a passage therethrough, a stem extending through the passage, a valve thereon normally closing said passage, manual means 90 for unseating said valve adapting inlet pressure to open the closure, means actuated by said stem adapted to manually open said closure to aid the inlet pressure and means 95 automatically seating said closure.
15. In a device of the class described the combination with a casing having an inlet and an outlet pipe of a valve seat intermediate the same, a differential closure therefor, a passage therethrough admitting inlet 100 pressure above the closure to unseat the same, a stem extending through the passage, means movable with the stem adapted to force the closure open wholly inclosed means actuated by fluid other than the valve fluid 105 to regulate the period of unseating the valve closure and means connected to the closure affording an afterfill.
16. In a device of the class described the combination with a casing having an inlet and an outlet, a valve seat in the casing, a differential closure therefor, a vent valve for 110 said closure adapted to admit pressure to open the same, a housing secured to the casing, a wholly closed cup therein operatively connected to control the rate of seating of the closure, said housing having communication with the external air both above and below the limits of movement of the cup, a 115 tubular stem extending into the cup having 120
- 125
- 130

- an aperture through its side, a piston thereon having a port through which the fluid flows freely in one direction, a stem threaded in the tubular stem to regulate the flow of fluid 5 through the aperture therein, a spring in the cup adapted to return the same to normal after each manual actuation and means integral with the closure and movable therewith to afford an afterfill.
- 10 17. In a device of the class described the combination with a casing having an inlet and an outlet of a valve seat in the casing, a differential closure therefor normally seated by inlet pressure, means admitting inlet 15 pressure to the larger area of the closure, manual means adapted to simultaneously contact the closure thereby opening the closure by both inlet pressure and manually, a wholly inclosed fluid containing cup, a 20 rigid piston therein, means rigidly engaged to the cup for manual actuation in starting the flush and operative connections between the cup and closure.
18. In a device of the class described the 25 combination with a casing of an inlet and an outlet therefor, a valve seat in the casing, a closure therefor, a cup in the casing above the closure, a piston in said cup and one of the same movable relatively of the other, a 30 stem engaged to the movable element and projecting through the closure having an enlarged end adapted to engage the closure to move the same in one direction, manually operated means actuating the stem to force 35 the enlarged end out of engagement with the closure and adapting the closure to be unseated by gravity, means automatically seating the closure and means in the cup adapted to control the rate of seating.
- 40 19. In a device of the class described the combination with a casing having an inlet and an outlet pipe, a removable valve seat intermediate said pipes, a closure adapted to seat thereon from beneath, a stem ex- 45 tending through the closure and into the inlet pipe, means connected with the stem adapted to contact the closure to unseat the same, a cup rigidly connected to the stem, means automatically raising the cup and 50 stem to seat the closure, an open chamber around the valve closure to provide an after fill and means in said cup through which fluid other than inlet fluid passes to control the movement of the valve closure in one 55 direction.
20. In a device of the class described the combination with a casing having an inlet and an outlet, a removable valve seat therein, a sleeve rigidly holding the same in place 60 provided with a plurality of apertures opening through the sides thereof into the outlet, a differential closure seating on the removable seat, a passage therethrough, a movable stem extending through said passage, a closure on said stem to close the pas-

sage, means connected with the stem adapted to be manually actuated to open the passage to admit inlet pressure above the closure to unseat the valve and means automatically closing the passage adapting the closure to 70 be seated by inlet pressure.

21. In a device of the class described the combination with a casing of an inlet and an outlet pipe therefor, a removable valve seat in the casing, removable means holding 75 the same in place, a valve closure for said seat, a chamber therein, a stem extending through the closure and chamber, a spider on said stem in the chamber adapted when the stem is manually actuated to unseat the 80 valve closure and a head on the end of the stem adapted when the stem is automatically actuated to engage the closure to seat the same.

22. In a device of the class described the 85 combination with a casing of an inlet and an outlet pipe therefor, a removable valve seat in the casing, a closure therefor, a cylinder in the casing affording a chamber in which the upper part of the closure moves 90 said cylinder adapted to firmly hold the seat in place and apertured to afford communication with the outlet; means acting automatically to seat said closure independently of inlet pressure and to firmly hold the same 95 seated, manually operated means actuating said automatically acting means adapting the closure to unseat by gravity when the inlet pressure is low.

23. In a device of the class described the 100 combination with a casing of an inlet and an outlet pipe therefor, a valve seat intermediate said pipes, a differential closure, automatic means adapted to firmly seat and hold the same seated independently of inlet 105 pressure, manually operated means actuating the automatic seating means whereby gravity alone is utilized to open the closure on low inlet pressure, a wholly inclosed fluid containing cup movable above the closure, 110 a packing box in the upper head of the cup, a stem extending therethrough and a rigid piston secured thereon through which the fluid in the cup passes to control the rate of seating.

24. In a device of the class described the combination with a casing of an inlet and an outlet pipe, a valve seat in said casing, a differential closure adapted to close the same, a closed movable fluid containing cup 120 in the casing, a stem thereon projecting through the closure having an enlarged end adapted to contact the closure to force the same to its seat, automatic means raising the cup to seat the closure, a stem rigidly engaged to the cup for actuating the same, thereby forcing the enlargement on said stem out of contact with the closure adapting gravity to unseat the closure.

25. In a device of the class described the 130

combination with a casing of an inlet and an outlet pipe therefor, a valve seat in the casing, a closure therefor, a stem extending through the closure and above and below the same, means on said stem adapted to engage the closure to manually move the same in one direction, means on said stem adapted to engage the closure to move the same to normal and fluid controlled means automatically moving the stem to seat the closure.

26. In a device of the class described the combination with a casing of an inlet and an outlet therefor, a valve seat intermediate the outlet and inlet, a closure therefor, a fixed piston in the casing above the closure, a cup movable relatively thereof, a stem engaged to the cup and projecting through and beyond the bottom of the closure, an enlargement on said stem adapted to engage the end of the closure when moving in one direction to seat the same, automatically operative means moving said stem in one direction, a stem rigidly engaged to the cup and adapted for manual actuation to move the aforesaid stem in the opposite directions and fluid in said cup to regulate the rate of seating of the closure.

27. In a device of the class described the combination with a casing of an inlet and an outlet pipe therefor, a valve seat intermediate the same, a closure therefor, means unseating the closure by inlet pressure and gravity, means automatically seating the closing independently of inlet pressure and fluid controlled means regulating the period of seating.

28. In a device of the class described the combination with a casing of an inlet and an outlet therefor, a valve seat in the casing, a closure therefor having a passage therethrough, means unseating the closure and seating the same, a plurality of ways depending upon inlet pressure and comprising a stem extending through said passage, an enlargement on the end thereof adapted to contact the bottom of the valve when moving in one direction means on said stem adapted to contact the same when moving in an opposite direction, manually operated means for operating said stem in one direction, a spring compressed thereby adapted to return said means to normal and regulable means controlling the closing of the inlet.

29. In a device of the class described the

combination with a casing having an inlet and an outlet, a cylinder rigidly secured to the casing, a cup movable in the cylinder having a fluid therein, a seat in the casing, a chambered closure therefor having a passage therethrough, a piston integral therewith, an apertured flange integral with the closure adapted to admit inlet fluid from one side of the seat to the other prior to seating of the closure, a stem rigidly engaged to the cup and extending into the casing, a spider on said stem in the chamber of the closure and an enlargement on the end of the stem adapted to close the passage through the closure.

30. In a device of the class described the combination with a casing of an inlet and an outlet therefor, a removable valve seat, a sleeve bearing against the top of the casing and firmly securing the seat in place and apertured to afford communication with the outlet, a closure for said seat having its upper part extending into the sleeve above the apertured portion, a vent valve in the closure, manually operated means for opening the vent valve adapting inlet pressure to act on the top of the closure in the sleeve to unseat the closure and inlet pressure adapted to seat the closure and means acting independently of inlet pressure to unseat and seat the closure.

31. In a device of the class described the combination with a casing of an inlet and an outlet pipe therefor, a valve seat in the casing, a sleeve rigidly secured thereto affording a chamber within the casing and apertured near the lower end to afford communication between the same and outlet, a chambered closure adapted to seat thereon having a passage therethrough, a fluid containing cup above the closure, a stem rigidly engaged thereto projecting through the passage in the closure and said chamber, means secured on the stem in the chamber adapted to contact the closure to aid in unseating the same and a valve on the stem beneath the closure to close the passage therethrough.

In testimony whereof I have hereunto subscribed my name in the presence of two subscribing witnesses.

ROBERT A. BROOKS.
